(57) **CLAIM**

The ornamental design for an exercise device, as shown and described.

DESCRIPTION

FIG. 1 is a perspective of an exercise device, showing my new design, wherein the handle assembly is detached;
FIG. 2 is a front elevation view of FIG. 1;
FIG. 3 is a rear elevational view of FIG. 1;
FIG. 4 is a top plan view of FIG. 1;
FIG. 5 is a bottom plan view of FIG. 1;
FIG. 6 is a right side elevational view of FIG. 1;
FIG. 7 is a left side elevational view of FIG. 1;
FIG. 8 is a perspective view of the exercise device, wherein the handle assembly is attached;
FIG. 9 is a front elevational view of FIG. 8;
FIG. 10 is a rear elevational view of FIG. 8;
FIG. 11 is a top plan view of FIG. 8;
FIG. 12 is a bottom plan view of FIG. 8;
FIG. 13 is a right side elevational view of FIG. 8; and,
FIG. 14 is a left side elevational view of FIG. 8.
